CHARLES PARENT, OF MEDFORD, MASSACHUSETTS.

TENSION DEVICE AND AUTOMATIC TAKE-UP.

1,113,243.

Specification of Letters Patent.

Patented Oct. 13, 1914.

Application filed April 16, 1913. Serial No. 761,438.

To all whom it may concern:

Be it known that I, CHARLES PARENT, a citizen of the United States, residing at Medford, county of Middlesex, State of Massachusetts, have invented a certain new and useful Improvement in Tension Devices and Automatic Take-Ups, of which the following is a specification, reference being had therein to the accompanying drawings.

10 The invention relates to a tension device and automatic take-up especially intended for use in braiding machines, such for instance as used in braiding shoe strings or braiding a cover on a wire, but it is adapted to be used in other classes of machines.

In the process of braiding as the racers travel around the race circles the distance between the thread holder and the point where one thread intersects another thread 20 varies constantly so that unless a suitable take-up is provided there will be frequent slack thread. With the take-ups in common use there is still frequently slack thread which the action of the take-ups is not 25 quick enough to wholly prevent.

The object of the present invention is to provide a quick acting take-up which will constantly keep the thread under proper tension.

30 The invention will be fully understood from the following description taken in connection with the accompanying drawings, and the novel features thereof will be pointed out and clearly defined in the claims at 35 the close of this specification.

In the drawings,—Figure 1 is a side elevation partly in section showing my improved tension device and take-up connected with a race plate of a braiding machine, showing the parts in position when the thread is under working tension. Fig. 40 2 is a side elevation of the parts shown in Fig. 1, omitting the connection with the race plate, showing the spool of thread partly used up and with the take-up attachment in the position that it will be in when the pull on the thread is relaxed. Fig. 3 is an enlarged view partly in section of the take-up device in its normal position when not under strain.

45 Fig. 4 is a side elevation of the take-up device under part tension, showing the lower thread arm in its turned position as it will be before the full tension is applied to turn the other arm. Fig. 5 is a section on line 50 5—5 of Fig. 3.

In the drawings,—1 is a strand of thread running from a coil 2 which is wound upon a bobbin 3 mounted on a spindle 4. The strand 1 is threaded through the tension device which is to be explained hereinafter and thence to the point where it is to be braided up with the other strands of thread coming from other bobbins. The spindle 4 is mounted in a frame or holder having a base 5 and a top 6 to receive the two ends of the spindle, the top 6 and the base 5 being tied together by a back 7. The top 6 is preferably hinged as at 8 to the back 7 so that it may be turned up on its hinge to allow the bobbin to be removed. The back 7 of the frame is secured to a racer 9 which travels in the race circle or path in the race plate 10. The racer 9 is provided with flanged heads 14, 14 to retain it in the race path. In the form of construction 75 shown the race plate is in a vertical plane, but the plane of the race whether vertical or horizontal is not essential to the present invention. The bobbin is somewhat shorter than the distance between the top 6 and 80 base 5 of the frame or holder. Saucer shaped heads or flanges 11, 12 are mounted loosely on the spindle at each end of the bobbin, the concave faces of the said heads being toward and resting against the ends of 85 the race of thread 2. Between the upper head 11 and the top 6 of the holder there is a saucer shaped spring metal disk or washer 13 which by pressure on the head 11 holds the said head 11 in engagement with the 90 end of the roll of thread and presses the other end of the roll into engagement with the head 12. On account of the concave form of the said heads 11, 12, it is obvious that the bearing of the heads on the ends of the 95 roll of thread will be in a circular line at the periphery of the roll and that as the roll is diminished in diameter the circular bearing line will diminish in diameter and therefore be nearer and nearer to the center of the 100 head. This allows the head 11 to settle or be pressed farther down over the end of the roll so that the end of the roll is nearer the top of the concavity. The lower end of the roll will also enter correspondingly farther 105 into the concavity of the head 12.

The spring washer 13 is normally concave. When the bobbin is full as in Fig. 1, so that the heads 11, 12 are the most widely separated from each other, the washer 13 110

will be compressed more nearly into a flat shape between the head 11 and the top 6 of the holder, but as the roll of thread is reduced in diameter and the head 11 is free to descend the tendency of the spring washer 13 to resume its normal shape presses on the head 11, and the spring washer becomes more and more concave. The heads 11, 12 should preferably be rigid so as not to change their degree of concavity. The pressure of the spring washer against the head 11 and against the top 6 of the holder caused by the tendency of the washer to assume a more and more concave form produces a friction between the spring washer and the top 6 and therefore serves as a brake to prevent too easy a turning of the bobbin on the spindle. As the coil of thread becomes smaller and smaller and the spring washer becomes more and more concave the tension decreases and therefore the drag on the rotation of the bobbin decreases. This is an advantage because the bobbin naturally rotates more freely when full and less freely as it diminishes in diameter by being drawn off and for this reason it is desired to have the tension of the spring washer greatest when the natural tendency of the thread is to run easiest so that one shall diminish as the other increases.

A shaft 15 extends from the top 6 to the base 5 of the holder, being mounted therein, preferably fixed so as not to rotate. Mounted on the said shaft 15 are two sleeves 16, 17, placed end to end with relation to each other, preferably of about equal length and meeting each other at or about the middle of the shaft. The lower sleeve 16 is formed or provided with an arm 18, preferably bent so that at first it extends at right angles to the sleeve 16, then a portion 19 toward the top plate and parallel with the sleeve, then again a portion 20 extending at right angles and away from the sleeve and formed with a thread eye 33. The upper sleeve 17 is formed or provided with an arm 21 which has a double bend similar to the arm 18, except that the second joint 22 extends toward the base 5, the third joint 23 extending at right angles with the sleeve and formed with a thread eye 34.

One of the arms 18, 21, may be made integral with its sleeve. In the form shown in the drawings the lower arm 18 is thus shown integral with the sleeve 16. The other arm is preferably radially adjustable in its connection with the sleeve 17. To this end it is provided with a split hub 24 through which the sleeve 17 passes, the arm 21 being also formed with a slit 25. By means of a screw 26 the split hub 24 may be turned on the sleeve 16 to adjust its position and then by setting up the screw again the hub will be held firmly in its adjusted position. A coil spring 27 surrounds the

sleeves 16, 17 between the arms 18, 21, one end of the spring being secured to the arm 18 and the other end of the spring being secured to the arm 21. By changing the adjustment of the hub 24, and therefore the radial direction of the arm 21, the tension of the spring 27 will be adjusted to a greater or less tension, as desired. Preferably the sleeves 16, 17 are reduced in diameter at the portions which are surrounded by the spring 27. A sleeve 28 envelops the spring 27 to protect it and keep it free from dirt.

Projecting from the sleeve 17 is an arm 29 which normally engages a stop pin 30 which projects from the top 6 of the holder. An arm 31 projects from the sleeve 16 and normally engages a stop pin 32 which projects from the base 5 of the holder. The tension of the spring 27 normally holds the arm 29 in engagement with the stop 30, and holds the arm 31 in engagement with the stop 32. The sleeve 17 with its arm 21 and the sleeve 16 with its arm 18 may be turned or rocked on the shaft 15, but one of said sleeves with its arm may turn independently of the turning of the other sleeve and its arm. The normal position of the arms is as shown in Fig. 2 with both stop arms 29, 31 in engagement with their respective stop pins 30, 32.

The device is threaded up when the parts are in their normal position, its thread passing from the roll 2 around the sleeve 28, thence through the eye of the thread arm 23, thence back around the sleeve 28 in the reverse order from the first turn around the said sleeve, thence through the eye of the thread arm 20, and thence to the braiding point.

When the machine is in operation, and the thread is having its strongest pull by reason of the largest distance of the racer or thread holder from the braiding point, the arms 18, 21 will both be pulled around from the position shown in Fig. 2 into the position shown in Fig. 1, with both arms pointing outward, and when they are drawn into that position the spring 27 will be coiled up tighter, increasing its tension. When the racer in its movement shortens the distance between it and the braiding joint, the lower arm, 18, will respond first to the pull of the spring in attempting to return to its normal position, as shown in Fig. 4, then as the distance still further shortens, the arm 21 will swing back to its normal position, as shown in Fig. 2, the slack being taken up by the winding of the thread around the take-up as shown in Fig. 2.

It is necessary that there should be sufficient tension on the spool or roll of thread to prevent its turning under the draft of the thread until the draft of the thread has turned at least one of the thread arms 18, 20 around from the position shown in Fig. 2

to the position shown in Fig. 4 or Fig. 1. This tension is produced by the spring washer 13.

What I claim is:

- 5 1. In combination with a bobbin, a holder for the bobbin, a tension device to prevent too free rotation of the bobbin and which is controlled by the roll of thread and which diminishes as the roll of thread diminishes
 10 10 in diameter, a movable take-up arm through which the thread passes from the bobbin and which is moved in one direction by the draft of the thread from the bobbin, and a tension device for the take-up which is put under
 15 greater tension by the movement of said take up arm caused by the draft of the thread, said last tension device causing the said take-up to move in the reverse direction to take up slack in the thread, said take-up
 20 tension at all times during the draft of the thread being of less strength than the tension on the bobbin whereby the draft on the thread will not rotate the bobbin until the take-up arm has moved far enough to take
 25 up the slack, the continued draft of the thread then rotating the bobbin while the bobbin tension still remains greater than the tension on the take up arm.

2. In combination with a bobbin, a holder for the bobbin, a tension device to prevent
 30 too free rotation of the bobbin, two rotary thread arms rotating on an axis parallel with the axis of the bobbin and both adapted to be threaded with braiding thread and tension mechanism which is adapted to rotate said arms in opposite directions to each other.

3. In combination with a bobbin, a holder for the bobbin, a tension device to prevent
 40 too free rotation of the bobbin, two rotary arms having thread eyes, and which when threaded up are turned in opposite directions by the draft of the thread, a spring which is put under tension by the rotation
 45 of either of said arms under the draft of the thread, and which when the draft on the thread is relaxed turns said arms backward in opposite directions to each other and takes up the slack of the thread.

- 50 4. In a braiding machine, a bobbin, two rotary thread arms rotating on an axis parallel with the axis of the bobbin and both adapted to be threaded with the braiding thread and tension mechanism which is
 55 adapted to rotate said arms in opposite directions to each other.

5. In a braiding machine, a bobbin, two rotary arms rotating on an axis parallel with the axis of the bobbin and having
 60 thread eyes, and which when threaded up are turned in opposite directions by the draft of the thread, a spring which is put under tension by the rotation of either of said arms under the draft of the thread, and
 65 which when the draft on the thread is re-

laxed turns said arms backward in opposite directions to each other and takes up the slack of the thread.

6. In a braiding machine, a shaft, two sleeves mounted loosely on said shaft and adapted to rotate thereon independently of each other, a thread arm having a thread eye projecting from each of said sleeves and rotating with the sleeves, both of said thread arms being rotated by the draft on the thread when threaded through said thread arms, a coil spring connected with each thread arm which is put under greater tension by the rotation of either thread arm under the pull of the thread and which slackens its tension when the draft on the thread is slackened, thereby rotating the said thread arm in the reverse direction and taking up the slack in the thread, and stops which limit the backward turn of the thread arms.

7. In a braiding machine, a shaft, two sleeves mounted loosely on said shaft and adapted to rotate thereon, a thread arm having a thread eye projecting from each of said sleeves, said thread arms being adapted to be threaded up so that the draft of the thread will rotate said sleeves and thread arms in opposite directions, a coil spring one end of which is connected with one of said arms and the other end of which is connected with the other of said arms and which is put under tension by the rotation of either or both of said arms under the pull of the thread, said spring actuating the reverse rotation of said arms when the pull of the thread is relaxed thereby taking up any tendency of the thread to slacken.

8. In a braiding machine, a shaft, two sleeves mounted loosely on said shaft and adapted to rotate thereon independently of each other, a thread arm having a thread eye projecting from each of said sleeves and rotating with the sleeves and which are rotated by the draft on the thread when threaded through said thread arms, a coil spring connected with each thread arm which is put under greater tension by the rotation of either thread arm under the pull of the thread and which slackens its tension when the draft on the thread is slackened thereby rotating the said thread arm in the reverse direction and taking up the slack in the thread, stops which limit the backward turn of the thread arms, and means for adjusting the radial direction of one of said arms with relation to the other whereby the initial tension of the spring may be varied.

9. In a braiding machine, a shaft, two sleeves mounted loosely on said shaft and adapted to rotate thereon independently of each other, a thread arm having a thread eye projecting from each of said sleeves

and rotating with the sleeves both of said thread arms being rotated by the draft on the thread when threaded through said thread arms, a coil spring connected with 5 each thread arm which is put under greater tension by the rotation of either thread arm under the pull of the thread and which slackens its tension when the draft on the thread is slackened, thereby rotating the 10 said thread arm in the reverse direction and taking up the slack in the thread, stops which limit the backward turn of the thread arms, and a sleeve which incloses said spring.

15 10. In a machine of the character described, in combination with a bobbin and a holder therefor, two rotary thread arms so arranged that they may both be threaded up with the same thread from the bobbin, and 20 so arranged that the draft of the thread may turn said thread arms in opposite directions to each other, and tension mechanism which prevents the said bobbin from rotating under the draft of the thread until 25 at least one of said arms has first been turned.

11. In a machine of the character described, in combination with a bobbin and a holder therefor, two thread arms so ar- 30 ranged that they may both be threaded up

with the same thread from the bobbin on its passage to the braiding point, at least one of said arms being rotatable, said thread arms being so arranged that the draft of the thread will turn said rotatable thread arm, and tension mechanism which prevents said bobbin from rotating under the draft of the thread until said rotatable arm has first been turned from its normal position.

35 12. In combination with a bobbin for a roll of thread, a spindle for the bobbin, a holder having bearings for the spindle in which the spindle rotates, a tension device to prevent too free rotation of the bobbin, a 40 movable take-up arm having an eye through which the thread passes from the bobbin and which is moved in one direction by the draft of the thread from the bobbin, and a tension device for the take-up which is put under 45 greater tension by the movement of said take-up arm caused by the draft of the thread.

50 In testimony whereof I affix my signature, in presence of two witnesses.
